UNITED STATES PATENT OFFICE.

FRANK SCHREIBER, CARL SCHREIBER, AND CHARLES E. FLAHRIDA, OF ZANESVILLE, OHIO.

GAS-FURNACE.

No. 866,688.

Specification of Letters Patent.

Patented Sept. 24, 1907.

Application filed February 28, 1907. Serial No. 359,886.

To all whom it may concern:

Be it known that we, FRANK SCHREIBER, CARL SCHREIBER, and CHARLES E. FLAHRIDA, citizens of the United States, residing at Zanesville, in the county 5 of Muskingum and State of Ohio, have invented certain new and useful Improvements in Gas-Furnaces; and we do declare the following to be a full, clear, and exact description of the invention, such as will enable others skilled in the art to which it appertains to make and use 10 the same.

This invention relates to improvements in gas burning furnaces.

The object of the invention is to provide a furnace of this character by means of which an even circulation of 15 air and heat is produced and means whereby the heated air is conducted from the furnace to the rooms or apartments to be warmed.

With the above and other objects in view which will appear as the nature of the invention is better understood, the invention consists in certain novel features of 20 construction, combination and arrangement of parts, as will be hereinafter more fully described and claimed.

In the accompanying drawings, Figure 1 is a vertical sectional view through the outer casing of the furnace; 25 Fig. 2 is a similar view through the furnace proper and the outer casing thereof; Fig. 3 is a horizontal sectional view taken through the combustion chamber on the line 3—3 of Fig. 2; Fig. 4 is a similar view showing the heat conducting pipes on the line 4—4 of Fig. 2; Fig. 5 30 is a similar view taken through the radiating drum on the line 5—5 of Fig. 2; and Fig. 6 is a plan view of the burner coils.

Referring more particularly to the drawings, 1 denotes the furnace proper which is inclosed by a cylindrical shell or casing 2 which may be formed of sheet iron or any suitable material and is closed at its upper end by a top 3 in which is arranged the hot air conducting pipes 4 by means of which the heated air from the furnace is conducted to the rooms or apartments to be 35 warmed. The furnace proper consists of an annular combustion chamber 5 having formed therein a centrally-disposed annular air passage 6, the walls of which form the inner side walls of the combustion chamber as shown. The upper portions of the outer walls of the 40 combustion chamber preferably incline or converge inwardly toward the upper end of the chamber as shown at 6 to form deflecting walls by means of which the flame from the burner is directed upwardly and inwardly towards a series of vertically-disposed heat conducting tubes 7 which are arranged in the top wall of the 45 combustion chamber and are connected at their upper ends to a radiating drum 8.

The drum 8 is preferably cylindrical in shape and has formed therein a centrally-disposed air passage 9 which

communicates with the lower air passage 6 of the combustion chamber and provides for the passage of cold air between the combustion chamber and radiating drum and also through the heat conducting tubes 7. Cold air in thus passing through the passages 6 and 9 and between the heat conducting tubes 7 is thoroughly 50 heated after which said heated air is conducted by the pipes 4 to the rooms or apartments to be warmed by the furnace.

The radiating drum 8 is provided with an annular partition wall 10 which is arranged therein between the 55 upper ends of the heat conducting tubes 7 and the inner wall of the drum. The partition 10 extends upwardly from the bottom to within a short distance of the closed upper side of the drum and forms a baffle plate by means of which the heat passing out of the tubes 7 is 60 forced to circulate through the drum before passing out of the discharge or fume pipe 12 which is connected to the radiating drum adjacent to the lower edge of its inner wall as shown at 13. The radiating drum is also provided with a series of vertically-disposed passages 70 14 which are arranged in an annular series around the drum between the upper ends of the heat conducting tubes 7 and the outer wall of the drum, as shown. The tubes 14 provide for an increased heating surface whereby the air from the lower end of the furnace in passing 75 upwardly will enter and pass through said tubes, and will be more thoroughly heated. By providing an increased heating surface for the radiating drum, the heating capacity of the furnace is materially increased.

Arranged in the combustion chamber 5 is an inner 80 burner coil 15 and an outer cylindrically arranged burner coil 16, said coils being provided on their upper sides with a series of gas outlets or burner openings. The burner coils 15 and 16 are provided with suitable supply pipes 17 which are adapted to be connected with 85 the gas service pipe, not shown.

The combustion chamber and furnace proper is adapted to be supported at a suitable elevation by means of legs 18 and in the lower side said combustion chamber is arranged a series of air supply pipes 19, the upper ends 90 of which connect with and open into the combustion chamber while the lower ends of said pipe extend through the shell or outer casing 2 of the furnace and communicate with the outside air, whereby the burner coils are supplied with the proper amount of air which 95 is evenly distributed throughout the combustion chamber to maintain a perfect combustion of the gas therein.

The upper inclined portion of the outer annular wall of the combustion chamber is preferably made double so 100 that one thickness of the metal may be removed and be replaced when the same becomes burned out. The inner wall of the double deflecting plate or inclined

upper portion of the outer combustion chamber wall is preferably lined with asbestos wool which materially aids in preventing the burning out of said plate and also causes the flame from the burner to become higher 5 and extend further upwardly into the heating tubes. The combustion chamber is provided in one side adjacent to the supply pipes 17 of the burner coils with a suitable door 20.

By constructing the heating tubes 7 in a cylindrical 10 form and arranging the same in an annular series around the upper side of the combustion chamber and providing air circulating spaces between said tubes, the cold air from the lower portion of the furnace in passing upwardly through the passage 6 will circulate freely 15 between and around said tubes and passing upwardly through the passages 9 and 14 in the radiating drum will become thoroughly heated by contact with the walls of the tubes and radiating drum and by the heat radiated from said parts so that a furnace constructed 20 in this manner will be capable of producing a maximum amount of heated air with a minimum amount of fuel.

From the foregoing description, taken in connection 25 with the accompanying drawings, the construction and operation of the invention will be readily understood without requiring a more extended explanation.

Various changes in the form, proportion and the minor details of construction may be resorted to without

departing from the principle or sacrificing any of the advantages of the invention, as defined by the append- 30 ed claims.

Having thus described my invention, what I claim as new and desire to secure by Letters-Patent is:—

In a gas burning furnace, the combination with an outer shell or casing, of a furnace proper arranged therein and supported above the bottom thereof, said furnace proper comprising a combustion chamber having formed therein, a centrally-disposed air passage, an inwardly-inclined outer wall on said combustion chamber to form a heat and flame deflecting plate, a heat radiating drum having formed therein a centrally-disposed air passage and an outer series of air passages, a series of heat conducting tubes connecting the top of the combustion chamber with the bottom of the heat radiating drum, a discharge or fume pipe connected with the inner wall of said radiating drum, 40 a baffle plate arranged in the drum between the inner wall of the latter and the heat conducting tubes to cause a circulation of heat through the drum, burner pipes arranged in said combustion chamber and a series of cold air conducting pipes connected with the lower wall of said chamber and with the outer shell or casing of the furnace whereby air is supplied to said combustion chamber, substantially as described. 50

In testimony whereof we have hereunto set our hand in presence of two subscribing witnesses.

FRANK SCHREIBER.
